D. S. WEDGEWORTH

TOOL

Filed Dec. 20, 1922

David S. Wedgeworth
INVENTOR

BY *Victor J. Evans*

Leotaype,

WITNESS:

ATTORNEY

UNITED STATES PATENT OFFICE.

DAVID S. WEDGEWORTH, OF SAUCIER, MISSISSIPPI.

TOOL.

Application filed December 20, 1922. Serial No. 608,037.

To all whom it may concern:

Be it known that I, DAVID S. WEDGEWORTH, a citizen of the United States, residing at Saucier, in the county of Harrison 5 and State of Mississippi, have invented new and useful Improvements in Tools, of which the following is a specification.

The object of this invention is to produce a simple, cheap and effective means for removing broken parts from steam valves, pipe sleeves, unions, ells, etc.

A further object is to produce a tool for this purpose which will grip and back out broken threaded pipe sections having either 10 right or left hand screw threads.

To the attainment of the foregoing and other objects which will present themselves as the nature of the invention is better understood, reference is to be had to the drawings which accompany and which form part 20 of this application, and in which:—

Figure 1 is an elevation of the improvement.

Figure 2 is a sectional view on the line 25 2—2 of Figure 1.

Figure 3 is a sectional view on the line 3—3 of Figure 1.

Figure 4 is a view looking toward one 30 end of the device,

Figure 5 is a perspective view of the blade or jaw expanding element.

My improved tool may be considered in the nature of an inside wrench, inasmuch as the same is designed to be arranged in a 35 pipe, valve or other hollow threaded member connected to grip and to remove broken parts therefrom.

The improvement essentially comprises a body or head portion 1, the same having its 40 outer end square in cross section and provided with a centrally arranged square bore 2. The squared end of the head 1 is preferably provided with a continuous outstanding flange or shoulder 4, the said shoulder, 45 at the center of its faces being formed with extensions in the nature of spaced ears 5. From the ears 5 the head is formed with a reduced cross sectionally rounded extension in the nature of a sleeve 6, and the said 50 sleeve, in a line with the confronting faces of the ears 5 is slotted, as at 7, the said slots also passing between the ears, and terminating in a line with the outer wall of the shoulder 4. The slots 7 may be arranged

angularly with respect to the longitudinal 55 plane of the head 1.

Pivottally secured between each pair of ears 5, as at 8 is the widened inner end portion 9 of blades or jaws 10, one of said jaws, of course, being received in one of the slots 60 7. If desired, the openings in the jaws through which the pivots 8 pass may be somewhat elongated, and each of the jaws has its outer face toothed or serrated, as at 65 11. The jaws 10 project a considerable distance beyond the tubular or sleeve end 6 of the head 1 and are of a width considerably greater than the thickness between the bore 2 and the sleeve end 6 of the head 1.

The blade expanding element is in the nature of a cross sectionally rectangular bar which is broadly indicated by the numeral 70 12. The bar 12 has each of its faces from its end that enters the bore 2 provided with longitudinal grooves 13, the said grooves 75 being deepest at the end of the bar, and from this point the said grooves gradually decrease in depth. Each of the grooves is designed to receive the inner and angle edge 14 of each of the jaws 10. By reference to the drawings it will be noted that the outer ends of the jaws are wider than the inner ends thereof, or in other words the said inner edges are arranged at an inclination.

In operation, the jaws are moved inwardly, the expanding bar 12 being drawn partly through the bore 2 of the head 1. The device is then inserted in a valve or pipe member in which there is a broken section. 90 The bar 12 is moved inwardly through the bore 2, causing the jaws 10 to be swung outwardly, so that their toothed outer edges will tightly engage the broken pipe section. A wrench is then employed for engaging 95 the cross sectionally rectangular bar to cause the tool as a whole to turn with the broken pipe section. The tool may be turned in either direction in accordance with the right or left hand threads which connect the broken to the unbroken pipe section. The inner edges of the jaws being received in the grooves of the bar 12, are materially reinforced and sustained from injury in the operation of the tool, and it is thought that 100 the foregoing description, when taken in connection with the drawings will fully set forth the simplicity of the construction, the 105

ease of operation and the advantages of the improvement to those skilled in the art to which the invention relates.

Having described the invention, I claim:

A tool for the purpose set forth comprising a head including a straight end terminating in a shoulder provided with projecting spaced ears on each of the faces thereof and having a tubular extension beyond the ears, said extension having angle slots which pass between the spaced ears, jaw members comprising blades having widened inner ends provided with elongated openings, one of said jaws being received in each of the slots, a pivot passing between

the ears and through the openings of the jaws, each of said jaws having its outer edge toothed or serrated and its inner edge disposed angularly with respect to its outer edge, said head having a squared bore, a cross sectionally squared bar received in the bore and having longitudinally extending angularly disposed grooves whose inner walls are deepest at the outer ends thereof, and each of said grooves designed to receive the inner edge of one of the jaws when the bar is moved inwardly through the head.

In testimony whereof I affix my signature.

DAVID S. WEDGEWORTH.
